(57) **CLAIM**

The ornamental design for an ultrasound biopsy device, as shown and described.

DESCRIPTION

FIG. 1 is a top perspective view of an ultrasound biopsy device, showing our new design;

FIG. 2 is a bottom perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof; and,

FIG. 8 is a bottom plan view thereof.

The needle assembly, collection assembly, latch assembly, button assembly, and cable assembly shown in broken lines are unclaimed subject matter and form no part of the claimed design.
